US00D817727S

(12) **United States Design Patent** (10) **Patent No.:** **US D817,727 S**
(45) **Date of Patent:** **** May 15, 2018**

(54) **FOOD EXTRUSION DIE**

(71) Applicant: **Frito-Lay North America, Inc.**, Plano, TX (US)

(72) Inventor: **Rogers Williams**, McKinney, TX (US)

(73) Assignee: **Frito-Lay North America, Inc.**, Plano, TX (US)

(**) Term: **15 Years**

(21) Appl. No.: **29/583,969**

(22) Filed: **Nov. 10, 2016**

(51) LOC (11) Cl. **07-04**

(52) U.S. Cl.

USPC **D7/672**

(57) **CLAIM**

The ornamental design for a food extrusion die, as shown and described.

DESCRIPTION

FIG. 1 is a first top perspective view of the present invention; FIG. 2 is a second top perspective view of the present invention;

FIG. 3 is a front elevation view of the present invention with the left elevation, right elevation, and rear elevation views identical to the front elevation view;

FIG. 4 is a top plan view of the present invention;

FIG. 5 is a bottom plan view of the present invention;

FIG. 6 is a first bottom perspective view of the present invention; and,

FIG. 7 is a second bottom perspective view of the present invention.

The broken lines illustrate environmental features that form no part of the claimed invention.
